METHOD OF AND APPARATUS FOR THE RECOVERY OF EXPLOSIVES FROM SHELLS

Filed Nov. 13, 1926

UNITED STATES PATENT OFFICE.

JOSEPH H. ROBERTS, OF NEW YORK, N. Y., ASSIGNOR OF ONE-HALF TO FRANK W. OLIN, OF EAST ALTON, ILLINOIS.

METHOD OF AND APPARATUS FOR THE RECOVERY OF EXPLOSIVES FROM SHELLS.

Application filed November 13, 1926. Serial No. 148,117.

My invention relates to new and useful improvements in the method of an apparatus for the recovery of explosives from shells and has for an object to provide a 5 method and apparatus whereby the explosives may be recovered from the shells much more speedily than has heretofore been possible.

Still another object of the invention is to 10 recover the explosives from shells in a way that will be far less dangerous than the methods now employed.

Heretofore, it has been possible to extract the explosives from the shells by running 15 water into the shell to dissolve the explosive, but the recovery of the ammonium nitrate from the solution by heat is a rather dangerous one and the crystals are somewhat hard to recover. Also the tri-nitrotoluene had 20 to be recovered by gravity as it is insoluble in water.

The object of the present invention is to provide a method and apparatus whereby 25 heated organic solvents are run into a plurality of shells to allow the explosives to dissolve and form a saturated solution, after which the solvent is allowed to cool and the crystals recovered are then passed into a centrifuge and thoroughly or partially dried.

Still another object of the invention is to 30 provide an apparatus and to use several forms of solvents for the recovery of the explosives, the choice of the solvents depending upon the type of explosives in the shells.

As is well known, the United States War 35 Department often sells a large number of shells and projectiles which contain explosives, which explosives have a commercial value provided they may be economically recovered or extracted from the shells.

Still another object to be mentioned is to provide a method and apparatus whereby a 40 relatively large number of shells, say 800 or 1,000 may be treated by placing them in a tank and subjecting the explosives therein to a hot organic solvent, so that after a 45 couple of hours of time, a saturated solution is obtained, after which the solution is allowed to cool and the explosive crystals or salts recovered and dried.

With these and other objects in view, the invention consists in certain new and novel methods and arrangements and combination

of parts as will be hereinafter more fully described and pointed out in the claims. 55

Referring to the drawing showing one form of apparatus for carrying out my new and improved method:

Fig. 1 is a diagrammatic view showing the apparatus and a plurality of shells in 60 position showing the manner in which the explosives are recovered.

Fig. 2 is a fragmentary sectional view showing the outline of a shell and the tubes extending within the shell. 65

Referring now more specifically to the several views, I will first describe the apparatus for carrying out my method of recovering the explosives from the shells, after which the method and the solvents used will 70 be described.

It will be understood at the outset that the drawings show only one form of apparatus and in fact only show as much of that apparatus as is necessary to illustrate how a few 75 shells are placed in a tank and treated while in actual practice the tanks and headers and other parts will be large enough and numerous enough to carry out the method with say 1,000 shells at the one time. 80

In Fig. 1, I have shown a portion of the platform 1, on which there will be constructed a large tank 2, which may have a capacity of say 1,000 gallons. This tank is also closed on its top and may have the cap 85 3 therein so that fresh solvent may be placed in the tank when necessary.

Arranged in the bottom of this tank may be seen a heating coil 4, having the inlet pipe 5, which will extend to a heating plant 90 (not shown). This tank 2 has a solvent outlet pipe 6, which leads to a header 7, and in actual practice there may be a large number of these headers, although I have only shown one for the sake of clearness of illustration. 95 There may be a number of small outlet pipes 8 from the header to each of which there will be connected a small pipe 9.

Directly under this header there is shown a part of another platform 10, on which platform there will be mounted another large tank 11, in which the plurality of shells will be placed to be treated. This tank 11 also is supplied with hot water by the inlet pipe 12, which pipe may be for 105 convenience connected with the supply pipe

5, which will be remembered supplies hot water to the heating coils 4.

The object of having hot water in the tank 11, is to transfer some of the heat to 5 the shells, so that the explosive in the shells will more readily dissolve when treated with a solvent as will be shortly described.

Of course the level of the water in the tank 11 must not extend above the top of the 10 shells, so I provide an overflow pipe 13, which may lead to a return hot water supply pipe 14.

Extending below the platform 10 is a large 15 return pipe 15, which in turn extends to what I term a working tank 16, also mounted on a small platform 16'. This tank is also closed as it is a desire to prevent any fumes or gases escaping to the atmosphere.

Leading from the working tank is the 20 large pipe 17 in which may be positioned a pump 18 and if desired a valve 19; this pipe 17 leads from a point at the side and near the upper portion of the tank or it may be placed at the top of the working tank if desired.

Referring again to the tank 11, there will 25 be noticed a plurality of shells 20, each of which have had their adapters or fuses removed so that a small cap (see Fig. 2) 21 may be placed in the nose of the shell, through which cap will extend a small supply pipe 22, that may be fastened by a union 23 to the inlet pipe 9, and likewise a further tube 24 extends through the explosive 25 to 30 the bottom of the shell while at its top it is fastened to a small union 26, which in turn is connected to the pipe 27 that leads into the large return main 15.

It is to be understood at this point however, that the cap 21 and the two pipes extending in the cap and the manner of connecting by unions to the pipe 9 is simply illustrative of one form of device for leading the solvent into the shells and any other 45 preferred form of placing these pipes in the shell and sealing the nose of the shell might be also used.

Referring for the moment to the working tank 16, there is shown an outlet pipe 28, 50 with a valve 29 thereon, and a pipe 30 that leads to a centrifugal drier or separator, better known as a centrifuge 31, which has a drive shaft 32, which in turn is suitably driven. An outlet pipe 33 from the centrifuge is shown, which is also provided with a 3-way valve 34, so that the solvents to be shortly described may either be discharged or may be driven through the pipe 35 back into the solvent tank 2.

60 In the main return pipe 15, at one end is shown a small discharge pipe 36, so that samples of the solution may be taken at various times.

As far as the specification has proceeded 65 it will be seen that I have provided a sol-

vent tank with a heating coil therein, a tank for holding the shells which will also have hot water therein, a working tank and a centrifuge which will be normally out of operation, so that the solvent in the tank 2 may pass into the shells, run into the working tank and again pass up into the solvent supply tank. Thus the solvents about to be described may be forced through the shells, 70 pass into the working tank and again pass to the supply tank and again through the shells, 75 as long as deemed necessary.

Referring now to the solvent, solute and the method of recovering the solute, or explosives, it might be mentioned that most 80 of the shells are filled with ammonium nitrate NH_4NO_3 and tri-nitrotoluene $\text{C}_6\text{H}_3(\text{NO}_2)_3$, which is commercially known as T. N. T. The shells often contain 50% of the one and 50% of the other and the explosive 85 is known as amatol.

It will be understood that the explosive is in a solid condition when in a shell and is in the form of a hard crystal mass, which might be likened in form to a lump of maple 90 sugar.

In some instances the shells are loaded 95 with 80% of ammonium nitrate and 20% of tri-nitrotoluene. If it is desired to recover the explosives in shells that are loaded with 80% ammonium nitrate and 20% of T. N. T., I use a 100% of 95% grade commercial ethyl alcohol $\text{C}_2\text{H}_5\text{OH}$. This alcohol is placed in the solvent tank 2 and I may use anywhere from five hundred to 100 one thousand gallons depending upon the amount of shells to be treated.

The solvent is then heated anywhere up to about 70 degrees C., but in any event not above its boiling point, and the shells are 105 also heated externally by hot water in the tank 11, which water is at about 70 degrees C.

It will be noticed that the solvent tank is elevated with regard to the tank containing 110 the shells and this solvent flows through the shells for a period of about two hours, it continuously flowing through the three tanks and inlets and outlets as heretofore described. The temperature of the solvent 115 is kept at all times near the 70 degrees C. The alcohol dissolves the ammonium nitrate and the heat also causes the T. N. T. to dissolve into the solution and I have found that after approximately two hours or two and one-half hours the solutes will have passed 120 into solution. It will be understood that the solutions we are now considering on evaporation or cooling leaves the solute in its original chemical condition. As before 125 stated after the solution is saturated the solvent tank 2 is drained, that is any solution in the tank is allowed to pass down through the shells so that all of the solution 130 is then within the working tank 16.

Here the solution is allowed to cool so that the crystals will form in this working tank, after which the solvent free from the greater part of the solutes is pumped from the top 5 of the tank 16 to the tank 2 and the wet crystals passed into the centrifuge where they are rapidly dried and then may be stored up or packed for shipment.

It might be mentioned at this point that 10 when the crystals are recovered they are recovered in a non-compact or loose form rather than in a mass formation. This is one of the most important features of the present invention, as the crystals after being 15 dried may be used in their recovered form, either for the manufacture of explosives or for use with dynamite.

In most of the methods now in use, where 20 only water or steam is used, the solutes have to be dried in a grainer as they are recovered in a thick mass formation, rather than in loose crystal form as in the present invention.

Should the shells be loaded with 50% of 25 ammonium nitrate and 50% of tri-nitro-toluene or T. N. T., I use a solvent consisting of 90% of 95% grade alcohol, together with 10% of benzol, because I have found that this addition of benzol increases the 30 solvent action when a higher content of T. N. T. is present. The action through the tanks and the recovering of the explosive of course is in the same manner.

Should the shells contain only T. N. T., I 35 may use a solvent consisting wholly of benzol or I have also found that carbon tetrachloride (CCL₄) may be used with good effect as a solvent for shells loaded with T. N. T. The temperature should be 40 closely watched as the boiling point of the carbon tetrachloride is 76.7 degrees C.

It is of course known that the vapors from benzol and the liquid are inflammable and when this is used the supply lines must 45 be air tight, whereas if carbon tetrachloride is used this is not an inflammable liquid and such great care does not have to be used.

From the foregoing it will be seen that I 50 have produced a method of and apparatus for the rapid recovery of explosives from shells and wherein a large number of shells may be subjected to the treatment at the one time.

Furthermore, the recovery of the explosives by causing them to dissolve in certain 55 organic solvents, permits the entire amount of explosives to be extracted from the shells and again it is not necessary to subject the recovered ammonium nitrate crystals to heat 60 to drive off the water, as in the old form, so that the danger of explosions are greatly reduced, as the only heat in the present method is produced by coils through which hot water may be run to heat the solvents 65 and shells. Lastly the solutes go into solu-

tion more quickly when the solvents mentioned are used rather than when water or steam are used, and the crystals may be quickly and safely partially dried in the centrifuge.

It will also be understood that the apparatus for the recovery might be built in several units, so that while one unit is cooling, the other unit may be working.

I do not wish to confine myself to the 75 exact organic solvents mentioned as others might be found to be of value, nor do I wish to be limited to the exact structure of apparatus as shown, as many slight changes might be made without departing from the 80 spirit and scope of the invention.

Having thus described my invention, what I claim is new and desire to secure by Letters Patents is:—

1. The method of recovering a solidified 85 explosive from a shell, consisting of placing the shell with its open end directed upwardly, sealing two pipes in the open end of the shell and forcing a hot organic solvent into and out of the shell, cooling the solution 90 that has passed through the shell and then running off a part of the solution and running the resultant crystals through a centrifuge to recover and dry the same.

2. The method of recovering solidified 95 explosives from shells which consists in sealing two pipes within the mouth of the shell and forcing a hot organic solvent within the shell and then forcing the hot organic solvent out of the shell, cooling the solution so that the 100 solutes are in a loose crystal form and subjecting the loose crystal solutes to a centrifuge to thoroughly dry the same.

3. The method of recovering solidified 105 explosives from shells which consist in subjecting the explosive in the shell to a continuous flow of heated alcohol for a period of approximately three hours, the alcohol with the dissolved explosives therein retained in a tank and allowed to cool, so that 110 the crystals will form, removing the cool alcohol and then subjecting the wet loose explosive crystals to the action of a drier.

4. The method of recovering solidified 115 explosives from shells which consist in subjecting the explosive in the shell to a continuous flow of alcohol heated to a temperature of 70 degrees for a period of approximately three hours, the alcohol with the dissolved explosives therein retained in a tank and allowed to cool, so that the said crystals will 120 form, removing the cool alcohol and then subjecting the wet loose explosive crystals to the action of a drier.

5. The method of recovering an explosive 125 of 80% of ammonium nitrate and 20% of tri-nitro-toluene from shells that consists in running a 100% of 95% grade of heated ethyl alcohol in the shells, draining the solution from the shells, cooling the solution 130

and draining off the solution, recovering the resultant explosive crystals in non-compact form and subjecting the same to a drier.

6. The method of recovering an explosive 5 from shells, which explosive is made up of ammonium nitrate and tri-nitrotoluene and known as amatol, which consists in subjecting the explosives to a solvent, heated to about 70 degrees C., continuously passing 10 the solvent through the shells for approximately two hours, cooling the solvent and draining off the same and subjecting the loose crystals of ammonium nitrate and tri-nitrotoluene to a drier.

15 7. The method of recovering amatol from shells which consists in providing a tank supplied with an organic solvent, heating the solvent, heating the shells, running the solvent into and out of the shells to a working tank, passing the solvent from the working tank back to the solvent tank and again to the shells, the solvent being heated to approximately 70 degrees C., the exterior of the shells heated to 70 degrees C., drawing 25 all the solution to the working tank and allowing the solution to cool to recover the loose crystals of ammonium nitrate and tri-nitrotoluene from the solution and subjecting the crystals to a centrifuge.

30 8. The method of recovering amatol from shells which consists in subjecting the amatol to a heated solvent, heating the shells from the exterior by hot water, draining the solution from the shells, cooling the solution 35 and draining off the same, recovering the amatol in the form of loose crystals and subjecting the same to a drier.

40 9. The method of recovering amatol from shells which consists in subjecting the explosives to the flow of an organic solvent, cutting off the flow of the solvents and draining all the solution to a working tank, allowing the solvents to cool and drawing off the

greater part of the solution after crystals of ammonium nitrate and T. N. T. are formed 45 and then subjecting the mass which is composed of crystals of two explosives to a drier.

10. An apparatus for the recovery of explosives from shells which consists of a tank, adapted to contain a solvent, a further 50 tank adapted to contain the shells and means adapted to permit a flow of solvent from the tank through the shells, means connecting with the tank containing the shells and the working tank, means for heating the 55 solvent tank and means for heating the tank containing the shells and means for forcing a solution from the working tank to the solvent tank and a centrifuge connected with the working tank.

60 11. An apparatus for recovering high explosives from shells which comprises a tank for organic solvents, a tank for the reception of shells and a working tank, means for heating the solvent tank and means for 65 heating the tank for the shells, means for connecting the shells with the solvent tank and means adapted to extend from the shells to the working tank, means connecting the working tank with the solvent tank and 70 a pump in the said means.

12. An apparatus for recovering high explosives from shells which comprises a tank for solvents, a tank for the reception of shells and a working tank, means for heating the solvent tank and means for heating the tank for the shells, means for connecting the shells with the solvent tank and means adapted to extend from the shells to the working 75 tank, means connecting the working 80 tank with the solvent tank, a pump in the said means and a centrifuge connected with the working tank.

In testimony whereof I affix my signature.

JOSEPH H. ROBERTS.
